UNITED STATES PATENT OFFICE.

CHARLES CABANA, OF BUFFALO, NEW YORK.

POLISHING MOP.

Application filed January 23, 1922. Serial No. 531,013.

My invention relates to improvements in polishing mops, and more particularly to that type embodying a frame or mop head, a handle connected to said frame or mop head, and a swab adapted to be removably applied to the frame or mop head.

Various forms of polishing mops are now in use, in which the swab is removably applied to the frame or mop head, but most 10 of these are objectionable since they require skillful manipulation in order to remove the swab from the frame or mop head or to apply the swab thereto.

The primary object of my invention is 15 the provision of a simple and inexpensive polishing mop in which the frame or mop head is formed of two relatively movable parts, each adapted to carry a portion of the swab and when moved relatively in one 20 direction, or what may be termed "closing position", in which the true outline of the frame or mop head is defined, the swab will be automatically clamped into position and also stretched on the frame or mop head.

Another object of my invention is to provide a polishing mop having a frame or 25 mop head comprising two pivotally-connected parts or members capable of being swung toward each other or away from each 30 other, one position of said parts or members permitting the ready attachment of the swab to, or the removal thereof from the frame or mop head, while in the other the swab is clamped and stretched on the frame 35 or mop head.

A further object is to provide a polishing 40 mop having a mop head gradually widened rearwardly from a substantially pointed front end and arranged to separate centrally along a longitudinal medial plane, the parts of the mop head at opposite sides of said longitudinal plane having a free 45 end over which a swab is adapted to be slipped, and which swab, when said parts are moved toward each other, will become stretched on the frame.

A still further object of my invention is 50 the provision of a polishing mop comprising a mop head having two pivotally-connected parts movable relatively in lateral directions, and means for clamping a handle to said parts and simultaneously therewith retaining the swab on said head.

With the above and other objects in view, 55 the invention consists in the novel features of construction and in the arrangement and

combination of parts to be hereinafter described and more particularly pointed out in the subjoined claims.

In the drawings:

Fig. 1 is a perspective view of my improved polishing mop showing the handle broken away near the connector or coupling of the mop.

Fig. 2 is a plan view of the same.

Fig. 3 is a perspective view of the frame or mop head showing the two pivotally-connected parts thereof slightly separated and a portion of a polishing swab in connection therewith.

Fig. 4 is a horizontal section in the plane of the frame or mop head, showing a swab slipped onto the two parts of the frame or mop head and said parts in separated position.

Fig. 5 is a transverse section through the pivot and surrounding parts.

Fig. 6 is a perspective view of a modified form of my improved mop, a portion of the polishing swab being shown in connection therewith and the handle broken away.

Fig. 7 is a central longitudinal section of my modified form of mop head; the polishing swab being removed therefrom.

Fig. 8 is an enlarged longitudinal section taken on line 8-8, Fig. 7.

The mop head comprises two relatively movable parts 9, 10 connected in any suitable manner. In preferred form, these parts are pivotally connected together so that both may be swung outwardly or laterally, for a purpose to appear hereinafter.

As shown in the drawings each part of the frame or mop head comprises a slender strip of metal formed to provide a straight-lined longitudinal inner member 11, a curved portion 12 at the rear end of said inner member, and a forwardly and inwardly-directed outer member 13 having preferably an abrupt inner bend or curve 14 at its front extremity. Each part therefore forms a loop pointed at its front end and gradually widened rearwardly with a semi-circular rear end. The two parts of the frame or mop head are formed of sheet metal, preferably possessing a degree of resiliency so that the forwardly and inwardly-directed outer members 13 may flex inwardly under certain conditions, to be hereinafter explained.

The straight-lined longitudinal inner members 11 have inwardly-directed flanges

- 15 along a portion of their upper edges, and one of these flanges overlies the other. A rivet or other suitable pivot 16 is passed through the overlying flanges at their front ends and serves to connect the two relatively movable parts 9, 10 together. The straight-lined longitudinal members 11 may therefore be referred to as parallel inner members, since these members are parallel 6 when the relatively movable parts are swung together or placed in what may be termed closed position.
- One of the inner members 11 has an upwardly-directed lip 17 at its upper edge a short distance in rear of the flange 15 thereof and the other has a lip or extension 18 similar to the lip 17 but provided at opposite ends with parallel inwardly-directed spacing arms 19, the outer ends of which are 10 adapted to abut against the inner side of the lip 17 on the first-mentioned inner member. Said lips 17 and 18 form what may be termed a spacing device to retain the inner members 11 in parallel relation.
- 15 When the two parts of the frame or mop head are brought together, said frame or mop head may be referred to as being closed, and when said two parts are swung outwardly or laterally, said mop head may be referred to as being opened. When the mop head is closed it is of substantially heart formation, thus providing a pointed end enabling the user to readily reach corners and effectively clean the same. The two parts 20 9, 10 of the frame or mop head are retained in closed position by a coupling whereby the frame or mop head is connected to a handle.
- In the drawings, 20 designates the handle which, however, is shown broken away, and 25 21 is the coupling or connector which is constructed of sheet metal formed or fashioned to provide a sleeve or ferrule 22 into which the handle is adapted to be inserted. Said sleeve or ferrule 22 has two spaced arms 23 at its lower end, which are adapted to straddle the spacing device extending upwardly from the inner members 11 of the mop head, one arm lying outside of the upwardly-directed lip 17 and the other outside of the lip 30 or extension 18. When the coupling or connector straddles the spacing device of the frame or mop head, the two parts of said frame or mop head are retained in closed position, and a pivot bolt 24 is passed 35 through said arms 23 and through the two parts of the spacing device, respectively, extending upwardly from the inner members 11 of the mop head, said bolt having a thumb nut 25 applied thereto. When tightening the pivot bolt by means of the thumb nut, the friction between the spaced arms and the two parts of the spacing device will be sufficient to retain the handle at any angle in which it may be placed, thereby allowing the same to be swung on the pivot 40 45 50 55 60 65

when greater pressure upwardly or downwardly is exerted against the handle than ordinarily applied during the use of the mop.

Each of the inner members 11 has pointed 70 prongs 26 stamped therefrom, preferably in the form of a longitudinal series, these prongs being directed forwardly and inwardly, as clearly shown in Fig. 4.

Applied to the frame or mop head is a 75 polishing swab 27, which is preferably formed of strips of fibrous material 28, such as cotton or the like, and threads or strings of cotton or other yarn 29 arranged in regular formation, along the center of which se 80 yarn and at opposite sides thereof the said strips of cotton or other material is sewed, as at 30. This provides an elongated flexible member having threads of suitable material hanging from opposite sides, and this 85 flexible member is folded or doubled upon itself longitudinally and sewed together, as at 31, to form a passage or tubular frame-receiving portion 32 which extends from one 90 end of said flexible member to the other. When thus folded, the strips of cotton or 95 other material line the threads surrounding the loop and face the threads around the loop so that the threads are fully concealed at the tubular portion of the mopping element and the exterior and the interior of the passage or tubular portion of the swab provided with smooth surfaces. This tubular portion may be referred to as a padded head 100 for the swab and it is preferably closed at opposite ends of the swab. At a point a certain distance from each end of the swab, the padded head or tubular portion is provided with openings 33, and only that portion of the passage or tubular portion between these openings is utilized for attaching the swab to the mop head. Therefore, if desired, the head or tubular portion of the swab may be closed from each of the 105 openings 33 to the adjacent end of the swab. 110

When applying the swab to the frame or mop head, the coupling or connector 21 is first detached from said frame or mop head. The two parts of the frame or mop head are then swung outwardly, or separated, as 115 shown in Fig. 4. The free end of the outer members 13 are then inserted through the openings 33 into the tubular portion or passage in the swab. The swab is next threaded or drawn rearwardly or outwardly until 120 the center of the same is substantially between the free ends of said outer members. This leaves the two end portions of the swab loose and these are taken hold of, one after the other, and placed against the inner sides 125 of the inner members so that the pointed prongs 26 will engage the same, as clearly shown in Fig. 4. With the swab thus positioned, the two parts of the mop head are 130 swung together. This action will cause the 130

swab to become stretched and the center of the same to be drawn tightly against the pivotally-connected front ends of the inner members, which serves as a backing for the portion of the swab extending through space from the free end of one outer member to the free end of the other. The stretching of the swab by closing of the two parts of the frame or mop head will cause the outer members 13 to be flexed inwardly and also assure penetration of the prongs 26 into the head of the swab, and as the combined normal thickness of the two parts of the head of the swab is greater than the space between the two inner members 11 of the mop head when closed, the parts of said head positioned between said inner members will be compressed and securely clamped, especially so after applying the coupling or connector 21 to the spacing device of said mop head.

By means of this construction a mop is provided having a pointed end fully padded at the point so as to prevent marring of furniture or other articles with which it may come in contact. It also provides a comparatively wide rear end for the mop and two stretches of the swab arranged centrally between the side members, thus furnishing a mop with a full yarn center. In fact, when viewed from the bottom, the cotton threads or yarn will occupy all space between the outlining portions of the mop and no portion of the mop head be visible.

In Figs. 5 to 8 I have shown a modified form of mop head and coupling wherein the inner members 11 are each provided with upward extensions or lips 34 of substantially circular outline, each lip having an axial opening 35 and being depressed inwardly from said opening toward the edge of the lip at its foremost point, as at 36, the parts so depressed forming guide grooves along or through which axial inwardly-directed bosses 37 formed on the arms 38 of the coupling or connector 39 are adapted to be passed after the handle is swung forwardly over the pointed front end of the mop head, as shown in Fig. 7. The two arms 39 of said coupling or connector are adapted to straddle the upward extensions or lips 34 with the axial inwardly-directed bosses 37 entered in the openings 35 and serving as pivots for the handle.

As clearly shown in Fig. 6, the arms 38 have circular extremities conforming in size to the extensions or lips 34. Each arm 38 has a lip 40 extending from its edge and when the handle is inclined upwardly and rearwardly, this lip is at or near the bottom of the arm. Each lip 40 is rebent inwardly and spaced from the inner face of the arm, as at 41, and these rebent lips or portions have inwardly-directed lugs 42 which are adapted to come in contact with

each other and hold the arms against inward movement. The rebent lips are adapted to engage and move in contact with the inner sides of the extensions or lips 34 when swinging said handle and at the same time preventing disconnection of the coupling or connector from said extensions or lips, except when the handle is swung in a forward direction to bring said lips to a position in line with or forward of the vertical center 75 of said lips.

Having thus described my invention, what I claim is:

1. A polishing mop including a mop head comprising two pivotally-connected parts 80 adapted to swing toward and away from each other, each part comprising a slender member curved into an open loop having a free terminal, an elongated swab having a tubular portion at one edge extending along its central region with openings at the ends of said tubular portion, portions of said slender members being adapted to be inserted through said openings into said tubular portion, and means on said slender members for retaining the end portions of said swab against said pivotally-connected parts.

2. A heart-shaped frame comprising two complemental looped members, each having substantially straight sides converging towards one end, the ends of the loop being spaced apart at the narrow end of the loop, and the members having their adjacent ends pivoted together, means to clamp the adjacent sides of said members together, and a swab having a tubular portion at one edge extending along the central portion thereof with openings at opposite ends of said tubular portion through each of which a portion of each part of said mop head 100 is inserted into said tubular portion, the end portions of said swab being positioned between said two complemental loop members and retained therebetween when said members are in close relation.

3. A polishing mop including a mop head comprising two parts, each part having an inner longitudinal member and an outer resilient member connected with said inner longitudinal member by a curved portion, corresponding ends of said inner longitudinal members being pivotally connected together and the free ends of said outer resilient members terminating in close proximity to the point of pivotal connection of said inner longitudinal members, a swab having a tubular portion at one edge along its central portion with openings at opposite ends of said tubular portion through which the outer resilient members of said parts are to be passed and entered into said tubular portion, the portions of said swab extending from said openings toward opposite ends being positioned between said inner longitudinal members, and means to keep the two

parts of said mop head in closed position to retain the end portions of said swab between said inner longitudinal members.

4. A polishing mop including a mop head comprising two relatively movable parts, said parts having parallel inner members and resilient outer members connected with said inner members by curved portions, said inner members having overlying flanges 10 pivotally connected together at one end and having also a plurality of pointed prongs stamped therefrom beneath said flanges, a swab having a tubular portion at one edge along its central portion with openings at 15 the ends of said tubular portion and through which openings the outer resilient members of said parts are inserted into said tubular portion, said swab covering said resilient members and the curved portions connecting 20 the same with said inner members, the end portions of said swab lying between said inner members and being engaged by one or more of said prongs, and means to connect a handle to said inner members and 25 simultaneously clamp said inner members together with the end portions of said swab therebetween.

5. A polishing mop including a mop head comprising two pivotally-connected parts, 30 each part being constructed of a slender metallic element formed to provide a straight-lined inner member and a resilient outer member connected at its rear end to the rear end of said inner member by a 35 curved portion and having its free end in proximity to the front end of said inner member, the inner members of both parts being parallel and separated by a narrow space and having their front ends pivotally 40 connected together, and a swab having a tubular portion extending along a portion of its length and having the resilient outer members and the curved portions connecting 45 said outer members with said straight-lined inner members enclosed within said tubular portion with the remainder of the swab lying against the inner sides of said straight-lined members and clamped therebetween.

6. A polishing mop comprising two complemental frame members, each of which 50 has a yielding outer side portion and a spaced substantially rigid inner side portion, means to clamp the inner side portions of said members together, and a swab having a tubular portion at one edge extending along the central portion thereof with openings at opposite ends of said tubular portion, said yielding side portions being 55 threaded into the tubular portion of the swab through said openings with the portions of the swab positioned between said two complemental members and retained therebetween when said parts are in close 60 relation.

65 7. A polishing mop, comprising a mop

head formed of two relatively movable parts, means for holding said parts together and retaining a handle on said mop head, and an elongated swab having a tubular portion at one edge extending along the greater portion of its length into which portions of said mop head are inserted and having loose end portions adapted to be clamped between the exposed portions of the mop head. 75

8. A polishing mop comprising a mop head having two relatively-movable looped parts pivoted at their ends to move toward and away from each other, each of said parts being widened rearwardly of the pivot and including a free ended resilient portion extending forwardly and inwardly, and a swab having a tubular intermediate portion slipped onto said free ended resilient portions and its end portions clamped between said two relatively-movable parts, said relatively-movable parts when opened permitting the swab to be easily placed in position thereon and when closed serving to stretch said swab on said parts. 85 90

9. A polishing mop, comprising a mop head having a substantially pointed front end and being widened rearwardly, said mop head being formed of two laterally-swinging members pivotally connected together at their front ends, an elongated swab carried by and stretched along said members and having its ends fastened to said parts and clamped therebetween, a handle for said mop, and a connector for 95 said handle connected with both parts of said mop head and keeping said parts in closed position while retaining the end portions of said swab in clamped condition between said parts. 100 105

10. A polishing mop comprising a mop head formed of two relatively movable parts, each part comprising a slender element looped between its ends to form a straight inner portion and a converging outer portion, the two inner portions being pivotally connected together at their front ends and having swab attaching means on their inner sides at said front ends, an elongated swab having its central point in line with and bearing against the pivoted ends of said inner portions and being supported by said outer portions from said central point toward the ends of said swab, the end portions of said swab being free and adapted to be secured to said swab attaching means when the parts of said mop head are separated, said swab being stretched along said slender elements and tightened around the mop head when closing the two parts thereof, and means for attaching a handle to the two parts of said mop head and simultaneously therewith retaining said parts in closed position. 110 115 120 125

11. A mop head having two complemen- 130

tal parts disposed at opposite sides of its longitudinal center, each part having a free ended resilient member capable of movement toward and from said longitudinal center, and a swab having a loop portion arranged between its ends along one edge thereof and receiving said free ended resilient portions, the loop portion of said swab being adapted to be stretched around said 10 mop head, and means for securing the ends of said swab to said mop head to tension the swab thereon.

12. A polishing mop including a mop head comprising two pivotally-connected parts, each including a free ended resilient portion and a swab having a loop along one edge intermediate the ends thereof into which the free ended resilient portions of said parts are positioned, and means for retaining the ends of said swab between said 15 20 parts.

In testimony whereof I affix my signature.

CHARLES CÁBANA.
